Primary Examiner — Paula Allen Greene(57) **CLAIM**

We claim the ornamental design for a headset, as shown and described.

DESCRIPTION

FIG. 1 is a top perspective view of a headset in accordance with the embodiment of the present design;

FIG. 2 is a front view for the headset in accordance with the embodiment of the present design.

FIG. 3 is a rear view for the headset in accordance with the embodiment of the present design.

FIG. 4 is a right side view of the headset in accordance with the embodiment of the present design.

FIG. 5 is a left side view for the headset in accordance with the embodiment of the present design.

FIG. 6 is a top view for the headset in accordance with the embodiment of the present design; and,

FIG. 7 is a bottom view for the headset in accordance with the embodiment of the present design.

The broken lines in the Figures show portions of the headset that form no part of the presently claimed design.
